ABSTRACT

In apparatus for processing yarn, spindles mounted on a rotatable arm are movable between two work stations by motive means. The latter is actuated by a sensor sensitive to the amount of yarn built up on a tube mounted on one of the spindles at a first work station. Following the arm and spindle movement, the yarn disposed on the one spindle is played out in a subsequent yarn processing step at a second station, while yarn continues to be wound in a substantially continuous manner about the other spindle disposed on said arm, which other spindle has been moved to the first station.

APPARATUS FOR CONNECTING TWO OR MORE WORKING OPERATIONS IN THE PRODUCTION, PREPARATION OR FINISHING OF YARNS

This invention relates to a process and apparatus for efficiently combining two or more operations in the production, preparation and/or finishing of yarns.

The cops produced on spinning machines, processing and/or finishing machines for yarn, cops, bobbins or windings of various types, after reaching the size determined by the machine or prescribed for the further processing, are conveyed by hand in conveyor boxes or by means of conveyor belts to the next processing machine operations.

In the meantime, the original machines are left with empty tubes and, by way of example, spinning or yarn twisting machines are brought into their starting position, and it is only after this preliminary step that the machine operation can be continued. It is understood that by removing the full cops or bobbins and the replacement therewith by empty tubes there arise stoppages, which impair the production efficiency of the machines. Equally or more significant in this connection, however, is the fact that the above replacement operation in many cases require a large number of personnel for the attendant unproductive conveying and storage operations.

These inefficiencies were recognized by various machine manufacturers whereupon they equipped their machines with mechanical or automatic devices for removing the full cops or bobbins. Success was attained, to be sure, in some cases in lowering the production and finishing costs of yarns, but simultaneously the apparatus investment and the space requirements increased. The prior art automatic machines are complicated, subject to breakdown and the conveying and storage operations are only partially reduced by them.

Other machinery manufacturers have joined two working processes into one working operation, but thereby made the speed of production dependent on the slower working process. Thus, there is known a texturizing machine in which the curling and the twisting steps are combined by means so that the curled yarn is wound directly onto a ring-twist spindle. The disadvantage of this otherwise labor-saving process, however, lies in the fact that the curling speed is not maintained in desired relation to the twisting speed and thereby the economy of this process has been lost.

Further, there are known machines which have available at each winding place or pirning head doubly or triply combined bobbin frames. After one bobbin reaches a predetermined winding diameter, the bobbin frame turns through 180° or 120° , brings the full bobbin out of engagement with the winding device and the yarn is then wound on the empty tube of the following bobbin frame part without interrupting the winding operation. Only after this do the operators remove the full bobbin from the bobbin frame and replace it with an empty tube.

This device for the bobbin change on the running thread is advantageously used, for example, in chemical fiber spinning machines or on machines in which any interruption of the winding process lead to difficulties in the resetting operation, or where the machines, because of a low winding speed and few thread breakages, run unattended in the night shift.

Underlying the present invention is the desire to combine two or more operating processes hitherto carried out separately, with only minimum intervention by the attending personnel, to avoid the conveyance of the

5 yarn between these processing locations, and to avoid the manual removal of the full cops or bobbins as well as their manual replacement with empty tubes. In the provided arrangement the large number of tubes hitherto necessary for the working operation is reduced to

10 two or three tubes per pirning head.

According to the invention, this is achieved in machines employed in spinning, twisting, winding and/or yarnfinishing processes by equipping such machines with at least two spinning, twisting or winding spindles 15 mounted on a rotatable arm or lever. After receiving the prescribed amount of yarn, the cops or bobbins are not removed from the spindles and replaced by empty tubes, but through a rotation of the combined spinning, twisting and/or winding spindles about an axis of the lever, the empty tube of the combined spindle passes into the working position for the first operating process, which is thus not interrupted, or only briefly interrupted.

25 The full cop, winding or bobbin of the combined spindle serves as a twisting or run-off spindle for the following processing step, whose operating speed is preferably greater than the speed of the preceding step. Regardless of the relative speeds, the spindle with the 30 unwound tube is available in time for the first working operation. If the second processing step is slower than the first, it is also possible to stop the preceding working operation until the second operation is completed. In the case of low thread speeds of the first operating 35 process, the yarn of several first working steps may be grouped whereby full cops or bobbins are successively fed onto a rapidly operating subsequent step of the process.

Further features of the invention are described with 40 the aid of the drawings, in which there are schematically represented several preferred forms of the invention, in various textile machines. The various inventive features noted in the drawings can be used in other forms of the invention individually or in any combination 45 on other textile machines.

FIG. 1 shows in front view a curling texturizing and 50 twisting machine which is equipped with the device for connecting the two operations;

FIG. 2 shows in side view a device for the simultaneous twisting, yarn finishing and after-twisting;

FIG. 3 shows in front view another device for producing multiple twists;

FIG. 4 shows schematically the twist construction of 55 the twist made on the device according to FIG. 3;

FIG. 5 shows in plan several spinning units of an OE spinning machine, from whose full bobbins in the reset position the yarn is unwound through a reciprocating automatic pirning head, cleaned and wound onto cross bobbins;

FIG. 6 shows in side view a ring spinning machine 60 with combined spinning and unwinding spindles which accomplish the unwinding of the yarn from the cops, the yarn cleaning and the winding onto the cross bobbins through a reciprocating pirning head;

FIG. 7 shows in side view a composite twist machine 65 employing combined ring-twist and uptwister spindles rotatably mounted on a lever.

DESCRIPTION OF THE INVENTION

In FIG. 1 there is represented in front view the unit of a curl texturizing and twisting machine. By means of two combined winding and twisting spindles per working position this machine is able to carry out the texturizing and the twisting without intermediate transportation of the bobbins with the curled yarn (and under special conditions without intervention of the operating personnel), simultaneously.

Endless yarns 1 and 2 to be texturized in FIG. 1 are conducted from run-off bobbins 3 and 4 through thread brakes 5 and 6 to delivery components 8 and 9 driven by shaft 7. From components 8 and 9 the yarns are conducted at the speed necessary for the curling to delivery components 11 and 12 driven by shaft 10. Between the delivery components, the thread tension required for the curling is maintained constant; from rotary tubelets 13 and 14 the endless yarn is rotated at the prescribed speed after passing through heater 15.

Yarns turned in Z- and S-directions, or also several curling yarns, coming from the delivery components 11 and 12, are wound by combined winding and twisting spindle 16 onto its disk bobbin 17. The bobbin driven at the periphery of winding body 18 by winding roller 19 runs at a constant peripheral speed corresponding to the texturizing speed. With the use of disk bobbins, thread guide 20 distributes the plied curling yarn parallel; on tubes, however, the yarn is applied in the form of a cross bobbin.

The combined winding and twisting spindle 16 in position I is fastened to arm 21 of a two-arm lever 23 rotatably mounted on bearing 22, and pressed by its own weight or additionally with weights and/or a spring on the winding roller 19. On second arm 24 of the lever 23 in position II there is fastened a further winding and twisting spindle 25, which with its whorl 26 is pressed against an endless belt or against disk 27 and is rotated by the latter at a high rate of speed.

Disk bobbin 28 illustrated on spindle 25 was previously in position I wound by the winding roller 19 and the thread guide 20 with yarns coming from the texturizing devices. From the spindle 25 rotating at 16,000 to 20,000 rpm., yarn 29 runs through balloon thread guide 30 at a constant winding speed onto bobbin 31. This winding device consists of bobbin roller 32, thread guide 33 and bobbin frame 34. At 16,000 rpm. and 80 T/min. of the twist, the winding speed is 200 m/min.

If the yarn 29 on the bobbin 31 is subsequently dyed, this is to be wound at a certain higher speed adapted to the contraction degree onto the bobbin 31. For this purpose there is to be interposed between the spindle 25 and the bobbin 31 a further yarn delivery mechanism 35.

The manner of operation of the device according to FIG. 1 is as follows: After disk bobbin 18 is wound with the prescribed amount of yarn, electric touch contact 36 may trigger drive mechanism 37 thus turning the lever 23 through about 180°, so that the spindle 16 with the disk bobbin 17 is lifted out of position I with the winding roller 19 and its whorl comes to a stop shortly before the contact point with the drive disk 27. Simultaneously, likewise through the revolution of the lever 23, the spindle 25 moves from position II into position I and its disk bobbin 28, from which yarn has been removed in the meantime, is placed against the winding roller 19, which drives the bobbin 28 at its periphery.

A device known in the art (not illustrated) cuts through the yarn section between the two disk bobbins and guides the yarn coming from the texturizing devices to the empty disk bobbin lying on the winding roller, without interrupting the curling process. The yarn end of the full disk bobbin in position II can be fed either by hand or by an automatic device (not shown in the drawing) through balloon thread guide 30 and delivery mechanism 35 to the bobbin 31, whereupon, 5 through the completion of the revolution of the lever 23 to 180° the spindle whorl is pressed on the disk 27, the spindle is set in rotation and through the interposition of the winding device with the bobbin 31 the twisting process, too, is continued.

10 The texturizing and twisting speeds must be related in such a way that the twisting process takes less time than the texturizing, which is directly achievable by the use of high-speed, combined winding and twisting spindles. If, however, say, because of thread breakages that 15 have occurred in the twisting, the disk bobbin in position II should not be empty in time, then the texturizing process on the corresponding curling devices can be interrupted until the completion of the twisting operation.

20 The device described in FIG. 1 can also be completed utilizing texturizing machines already on hand. In these cases it is more advantageous not to wind the texturized yarns onto the winding devices of the texturizing machine and to combine their winding spindles into winding and twisting spindles, but the yarns are to be guided over thread guides and/or rolls to the winding and twisting spindles which are mounted on a stand beside the texturizing machine.

25 Likewise over thread guides the yarn wound and 30 twisted on the stand according to the invention can be wound onto the winding devices of the texturizing machine. The long running paths of the untwisted and of the twisted yarn allow the interpositioning of various thermal and/or chemical treatments of the yarn. It is also possible, however, to equip the stand with reel devices and to texturize, twist and reel in strings of the texturized yarn in one operation.

In certain texturizing processes there can be achieved 35 such high texturizing speeds that the texturizing, as seen from the viewpoint of speed, no longer stands in desired relation with the twisting on the combined winding and twisting spindle. In such cases, instead of the normal final winding place there can be used a further device, already described, consisting of a rotatably 40 mounted lever and two combined winding and twisting places, whereby the twisting speed can be increased to 400 to 500 m/min. In another case, in one operation the pretwisted yarn is after-twisted on a ring-twist spindle or a DD twist spindle, which likewise leads to a 45 higher total twisting speed.

An apparatus for the simultaneous after-twisting of 50 endless yarns or for the twisting of plied yarns, their treatment, finishing, and for the twisting together of several pretwisted twines on one machine is schematically 55 represented in side view in FIG. 2.

On upright twister spindles 39 and 40 rotatably 60 driven by endless belt 38 there are slipped bobbins 41 and 42 with unturned endless yarn or plied yarns. Twisted twines 43 and 44 from the spindles 39 and 40, or depending on desired twist construction, also of 65 twines coming from several spindles are drawn off by draw-off roller pair 45, whose draw-off speed in combi-

nation with the turning rate of the spindles determines the twist of the twines 43 and 44, drawn off from the bobbins 41 and 42, plied over guide roll 46 to yarn treatment device 47.

Delivery mechanism 48 delivers the plied yarns, treated in the treatment device 47 to cross or disk bobbin 51 driven by winding roller 49 on the periphery and mounted on combined winding and twisting spindle 50, on which the plied twines are distributed. Depending on the winding type of thread guides 52, the ply yarns are distributed parallel or in crossed relation.

The speed of the delivery mechanism 48 is adjustable in such a way with respect to the speed of the draw-off roller pair 45 that the ply yarns in the yarn improvement device can be stretched or relaxed. The spindle 50 in position III is slidably fastened to arm 53 of lever 55, rotatably mounted on bearing 54, to slide in slot 56 in such a way that the bobbin 51 is pressed by pressure spring 57 onto the winding roller 49.

To the other arm of the lever 55 in position IV there is slidably fastened a second winding and twisting spindle 58 adapted to slide in slot 59. When the bobbin 51 has reached the desired diameter, turning device 60 receives from sensor 61 a signal to turn the lever 55 through 180°, whereupon the spindle 50 with the full bobbin 51 passes out of position III into position IV, whorl 62 of which, however, cannot be pressed by the pressure spring an endless belt 63 until stop 64 is operated by hand or mechanically, to release the spindle.

Simultaneously, through the revolution of the lever 55 the spindle 58 comes out of position IV into position III, whereupon by pressure spring 65 the spindle 58 with its tube, that has become empty in the meantime, is pressed on the winding roller 49 and the winding process continues on this tube. By a known device (not illustrated) the plied yarns between the spindles 50 and 58 are simultaneously severed, for example by a shear, so that the winding of the plied yarns onto the empty tube is assured.

After the process described, the twister draws the plied twist ends from the bobbin at rest in position IV through balloon eye 66, draw-off roller pair 67, if necessary, through a further yarn finishing device 68 over delivery mechanism 69 to tube 70 of a winding device. The latter comprises essentially winding roller 71, tube support 72 and thread guide 73. Through the operation of lever 74 on the stop 64 the spindle is freed, set in rotation by the endless belt 63 and the second twisting process is initiated by the application of the tube 70 in the tube support 72 to the winding roller 71. The connecting of two twisting processes and the possible interposing of one or more yarn improvement processes renders the apparatus of FIG. 2 especially suitable for the production of hand-knit yarns of wool or high-bulk yarns. Since in the second twisting operation the yarn of several bobbins of the first twisting process is twisted together, the bobbins on the tube 70 can be made very large, which is advantageous for the further processing.

It is also possible, however, by means of the device according to the invention already described to engage at the outlet end also a further working process, in hand knitting yarns, which, for example, could be the winding of balls.

As in the device of FIG. 1, however, it is also important in the multiple twist device of FIG. 2 that the last working process run fastest in time, since otherwise there occur stoppages which impair the efficiency of

the device. In the device of FIG. 2 this desideratum is present, for the twist of the second twisting operation is generally considerably lower than the twist of the first twisting process and because of the heavier yarn, in the second twisting operation thread breakages rarely occur.

In FIG. 3 there is represented a further multiple twist device in front view, which is especially suited for the production of technical twist yarns in one operation by means of the provided invention.

The device in FIG. 3 consists of two DD twist spindles 75 and 76, on which there are slipped cross bobbins 77 and 78 wound with plied yarn. Above the twist spindles there are placed cross bobbins 81 and 82 likewise wound with plied yarn. Yarns 83 and 84 of bobbins 77 and 78 are fed through hollow shafts of the DD twist spindles in common with plied yarns 85 and 86 coming from the bobbins 81 and 82, which previously were fed through thread brakes 87 and 88, balloon eyes 89 and 90 and over storage plates 91 and 92 to the DD twist spindles, through perforated spindle whorls 93 and 94 and plied by thread guide 95, wound on bobbin 96 of winding and twisting spindle 97.

In each revolution of the DD twist spindle storage plates 91 and 92, the plied yarns 83, 84, 85, and 86 in section A receive a twist, for example in S-direction. In section B, therefore, in the perforated DD spindle whorls 93 and 94 the yarns thus twisted are twisted together in the same twist number but in Z-direction.

As soon as bobbin 96 of winding and twisting spindle 97 is turned through 180° on arm 98 of a lever rotatably mounted on bearing 99, as already described in the preceding examples, the yarn coming from the DD twist spindle is further wound without interruption on the empty tube of winding and twisting spindle 101 on second arm 102 of lever 100.

From the winding and twisting spindle in the twisting position the twist yarn is conducted to tube 103 which is fastened in bobbin frame 104, over deflection roll 105 and thread distributor 106. With the pressing-on of the winding and twisting spindle in the twist position on endless belts 107 and the placing of the tube 103 on winding roller 108 the third twisting process is initiated.

The twist construction produced in the device according to FIG. 3 is schematically represented in FIG. 4 with the corresponding twist direction of the individual twist components.

In the embodiment above described it was expedient that the working processes joined into one operation have equal working speeds, or more advantageously, the second working process, from the viewpoint of time requirements, should be somewhat shorter than the first. The process according to the present invention makes possible, however, also the grouping together of working processes whose production speed differences are very great.

In FIG. 5 there is represented as an example in plan view a group of OE spinning units, from whose bobbins in the rest position the yarn is wound off by a reciprocating automatic winding device, knotted together, cleaned and rewound on cross bobbins suited for the further processing.

Yarn 110 spun in spinning rotors 109 is drawn off in OE spinning machines ordinarily by draw-off rollers 111 from the spinning rotors and by thread guides 12 distributed on the bobbins lying on winding rollers 113. The winding places of the OE spinning places in FIG.

5, however, are not, as hitherto usual, equipped with a simple bobbin frame for the support of the bobbins, for each spinning place there are provided two combined winding and run-off spindles 118 and 119 fastened to arms 114 and 115 of lever 117 rotatably mounted in bearing 116.

At the commencement of the spinning, the spinner conducts the yarn 110 spun by the spinning rotors to the winding and run-off spindles 118. Diameter sensors 120 initiate, after the reaching of the desired bobbin diameter, similarly as in the devices already described, the turning of the lever 117 through 180°, so that thereupon the yarn continues to run onto the empty or incompletely wound bobbin of the winding and runoff spindle 119, without interruption of the spinning process.

Automatic pirning head 123 running along the spinning machine, for example on rails 121 and 122, is equipped with suction nozzle 124 and drive roller 125. Head 123 winds off from several combined winding and run-off spindles successively or is actuated by a programming device controlled by the bobbin standing longest in the rest position.

As soon as winding device 123 stops at bobbin 126 to be wound off, the drive roller touches the surface of the bobbin or disk 127 provided for this purpose and placed on the winding run-off spindle and begins to drive the bobbin 126 slowly so that yarn suction nozzle 126 can suck up yarn end 128 from the bobbin 126 and feed it to knotting device 129 of the automatic winding device 123. The knotting device knots the yarn end 128 with the yarn end of cross bobbin 130 and initiates the winding-off of the yarn from the bobbin 126.

In the case of a thread breakage, as is usual in automatic cross-winding devices, the cross bobbin 130 is stopped, and in the case of a yarn fault the yarn is additionally severed, for example, by an electronic yarn cleaner. Known devices guide both yarn ends into knotter 129 and after the knotting together of the yarn ends, a sensor initiates the further winding.

In the device described, the yarn drawn off radially from the bobbin 126 drives the winding and run-off spindle 119. The mass accelerations occurring and a possible advance running of the bobbin can limit the draw-off speed and lead to unnecessary thread breakages, for which reason it is in many cases more advantageous to draw off the yarn from the bobbin 126 axially, in which case the spindle 119 does not have to rotate with the bobbin 126.

For this purpose it is necessary to equip the spindles 118 and 119 on the lever 119 with an additional joint over which the bobbins in the run-off position are erected by the automatic cross bobbin device through additional arrangements before the winding off.

In order to simplify the winding off of the yarn from the bobbins in the rest position, the automatic cross-winding device 123 can, depending on the spinning speed, wind off the yarn for a predetermined time at each spinning place and thereupon move to the next bobbin in the rest position, without regard to whether the yarn on the bobbin 126 was entirely wound off or the automatic cross bobbin device is at a standstill for a time because of the premature running off of the yarn. Without interrupting the spinning process, also winding and run-off spindles with partially wound bobbins can be brought by the lever 117 into the spinning position and the winding of the new yarn can be contin-

ued on these bobbins, since in the course of time the thread breakages distribute uniformly in all the working places.

The number of the spinning places allocated to a moving automatic pirning head will, however, in this case be smaller and it can also occur that some bobbins at working places with many thread breakages have to be removed by hand from the winding and run-off spindle.

10 The device in FIG. 5, however, can also be formed in such a way that several automatic cross-winding devices run in succession along several spinning machines and eject the full cross bobbins with the cleaned yarn at a certain place from their winding spindles into a 15 container and replace them by empty tubes, for example, from a magazine.

In FIG. 6 there is represented in side view a ring spinning machine with spinning spindles rotatable about an axis by which the spinning, the winding off of the yarn 20 from the cops, the yarn cleaning, and the winding of the yarn from several cops onto one cross bobbin take place simultaneously on a machine.

Each spinning place of the ring twist machine is equipped with two combined spinning and run-off spindles 133 and 134 borne on lever 131 about axis 132. If cops 135 on spindles 133 are full, the spinning machine, as usual, stops the spinning operation and after the formation of upper winding reserve 136, ring rail 137 is driven up out of its working position into position C, so that the spindles 133 and 134 are not hampered in their rotation through 180°. After completion of the rotation, the spindle 133 with its full cop 135 comes out of the spinning position into the wind-off position, the spindle 134 with the tube in the meantime wound off, however, moves into the spinning position. Here, however, care must be taken that the yarn remains in runner 138 of ring 139.

Before the new spinning cycle, the ring rail 137, by means provided for this on the ring-spinning machine, 40 passes into its starting position and the spindle now standing in the spinning position is turned about 8 to 12 times by drive band 140, in order to form the underwinding necessary for the further spinning. The yarn necessary for this is drawn off from the cop standing in the run-off position and thereupon the yarn piece between the two spindles is cut off by shears, whereupon the new spinning operation can commence.

Over the run-off spindles 134 on rail 142 there runs automatic cross-winding device 143, whose operation corresponds essentially to that of the winding device described in FIG. 5. The upper winding 136 is drawn off by suction funnel 144 of the automatic winding device and the yarn is fed to a knotter which knots together the yarn beginning of the cop with the yarn end 50 of the cross bobbin. In the case of a thread breakage in the section between the cop and the automatic winding place 143, the suction funnel 144 again feeds the yarn from the cop. After the winding off of the yarn from the corresponding run-off spindle 134, the automatic winding device on the rail 142 runs to the next spindle in the run-off position and repeats the process described.

The devices according to FIG. 5 and FIG. 6 can also be formed in such a manner that to each spinning place there is allocated a cross-winding place and only the actual knotting device with the suction nozzle and the electronic yarn cleaner moves between the spinning and run-off spindles in the wind off position. In any

case, care must be taken that during the changing process of the spindles, the winding devices do not disturb this operation. This time can be well utilized, for example, for depositing the full cross bobbins from the winding devices and for setting the empty tubes on the winding spindles.

In FIG. 7 there is represented in side view a combined ring-twist and uptwister twisting machine. In order to achieve high twisting performances with good twist drop-out, it is, in many cases advantageous to subdivide the twisting process into two operations independent of one another. The plied yarn is first pretwisted on a ring-twist machine with relatively low twist at high thread speed and thereupon after twisted on an uptwister twist machine which permits operating at a high spindle turning rate.

These steps of the twisting process can be connected in one operation by means of ring-twisted and uptwister spindles rotatable about an axis as in the device according to FIG. 7. Plied yarns 154 drawn off from bobbins 145 and 146 by delivery mechanism 147, fed to combined ring-twist and uptwister spindle 151 through balloon eye 152 and runner 153, are pretwisted at about $\frac{1}{3}$ of the intended twist number or at the highest possible turning speed of the runner 153 with high yarn delivery speed. If the twist cop standing in the ring-twist position or disk bobbin 155 is wound with yarn, the device stops the ring-twist operation. Ring rail 156 is raised in the arrow direction, so that through a rotation of lever 150 through 180° the combined spindle 151 with the full disk bobbin can pass into the uptwister position and combined spindle 157 on arm 158 of the lever 150 can pass into the ring-twist position.

Before the setting in operation of the two twisting processes, the ring rail 156 is brought back into the starting position through several turns of the spindle standing in the ring-twist position, the underwinding necessary for the ring-twisting, with already pretwisted plied yarn is drawn off from the spindle now standing in the uptwister spindle position and thereupon the yarn piece between the two spindles is severed.

From a twist programming device (not illustrated) the ring-twisting cycle can now be again initiated, in which process the twister at the spindles which accidentally are running without yarn, which may have been caused, for example, by the jumping of the yarn out of the runner or through a poor underwinding, is threaded by twisting the yarn into the device. The yarn end of the spindle standing in the uptwister position with the pretwisted yarn is fed by a device not represented or by the twister, as already described in the preceding examples through balloon eye 159 and delivery mechanism 160 to tube 161. After the releasing of a blocking device, whorl 162 of the spindle is pressed in the uptwister twist position against endless belt 163 and through the applying of the tube to winding roller 164 the second twisting process is initiated.

In the case of very heavy yarns as, for example, in the case of carpet yarns which are twisted into a Mouline yarn with relatively low twist number, the efficiency of the twisting machines even with large cops or disk bobbins is very poor, since the actual twisting stands in an unfavorable time relation to the removal of the full cops from the spindles and the slipping on of the empty tubes. With the device described in FIG. 7, through the use of two spindles per twisting place the down times of the twisting machine can be greatly reduced, as the

yarn from the spindle not in ring-twist position is wound simply through the balloon eye and the delivery mechanism onto the tube 161, without turning the spindle in the process.

5 In the embodiments described for the connecting and/or for the simultaneous execution of several working processes on one machine or a machine group, the connecting element consists of elements executing two functions. It is, however, also possible in the event that 10 it is expedient, to use also three or more combined spinning, twisting or winding spindles. As a device for changing the working process connecting elements, it is not always necessary to use a two-armed lever and for the process to take place through turning this lever 15 through 180° .

It is, for example, possible to carry out the process by a shifting of two or more combined spindles in one or also in several directions.

What is claimed is:

1. Apparatus for performing at least two steps in the production of a yarn product, the combination comprising a first yarn winding spindle, a first winding tube seated thereon, a yarn unwinding spindle having a second winding tube seated thereon, said yarn winding and said yarn unwinding spindles and said first and said second winding tubes seated thereon being movable between first positions of use and second positions of use assumed when employed in said two steps; common support means for said winding and said unwinding spindles and tubes seated thereon for alternately moving said spindles between said first and second positions of use without removal of said tubes seated thereon; said yarn winding and said yarn unwinding spindles functioning as yarn winding and yarn unwinding spindles, respectively, in said first positions of use and as yarn unwinding and yarn winding spindles, respectively, in said second positions of use; said winding and unwinding spindles when functioning as winding spindles being employed in the first of said steps, said winding and unwinding spindles when functioning as unwinding spindles being employed in the second of said steps.

2. The apparatus of claim 1 in which said common support means comprises a pivotally mounted arm and 45 is in combination with means for driving said winding and said unwinding tubes, and means sensitive to the size of one of said tubes for actuating the arm to move.

3. The apparatus of claim 1 in which apparatus employed in conjunction with said spindles in said first position of use includes yarn-texturizing means having yarn run-off bobbins, thread brakes controlling the yarn passing from said bobbins, delivery elements receiving the yarn from said brakes and delivering said yarn to said first winding tube disposed in said first position of use.

4. The apparatus of claim 1 in which apparatus employed in conjunction with said first winding tube in said first position of use includes upright twister spindles having seated thereon yarn unwinding bobbins from which yarn is drawn, a yarn treatment device for receiving yarn from said twister spindles and from which the yarn passes onto said first winding tube in a first position of use; said first winding tube being moved by said support means upon reaching a desired diameter to said second position of use whereat the spindle on which said first winding tube is mounted functions as an unwinding spindle for feeding yarn, and a second

yarn treatment device for receiving yarn from said unwinding spindle.

5. The apparatus of claim 1 in which the apparatus employed in combination with the first winding tube in the first position of use includes a plurality of double twist spindles on which are seated cross bobbins wound with plied yarn; said bobbins feeding said first winding tube disposed in said first position of use; said first winding tube being moved by said support means into said second position of use upon attaining a predetermined diameter whereat said twisted yarn is further twisted and unwound from said first winding tube onto a winding roller; the spindle on which said first winding tube is mounted comprising a twist spindle.

6. In combination, a plurality of spinning units having rotors from which yarn is drawn off and simultaneously wound on a plurality of first winding tubes of apparatuses as recited in claim 1 disposed in first positions of use; said first winding tubes being moved by their support means after attaining predetermined diameters; actuators sensitive to the sizes of said first winding tubes for actuating said support means to move said winding tubes to said second positions of use; an automatic pirning head movable along said first winding tubes in said second position of use of successively unwinding the yarn from said first winding tubes which have been moved into said second position of use by

their support means.

7. The combination of claim 1 in which a ring spinning machine having a ring rail provides yarn to said first winding tube in the first position of use, and a sensor sensitive to the size of said first winding tube adapted to urge said ring rail away from the first winding tube upon the latter reaching a predetermined size; said sensor also actuating the support means to move said first winding tube into said second position of use 10 wherein the second step is carried out; and an automatic pirning head movable along a path adjacent said first winding tube in said second position, adapted to unwind the yarn on said first winding tube.

8. The combination of claim 1 in which supply bobbins feed plied yarn to said first winding tube in the first position of use; delivery rollers and an axially movable ring rail engaging said plied yarn and interposed said supply bobbins and said first winding tube; said ring rail being movable into spaced relation with said first winding tube in the course of movement thereof by said support means; the spindle on which said first winding tube is seated functioning as an upright twister spindle; and a receiving roller for receiving the yarn from said first winding tube, in the course of which the yarn is again 20 twisted when said first winding tube is in said second position of use.
